UNITED STATES PATENT OFFICE.

JAMES B. ANDERSON, OF SHALER TOWNSHIP, ALLEGHENY COUNTY, PENNSYLVANIA,
ASSIGNOR TO PEOPLES NATURAL GAS COMPANY, OF PITTSBURGH, PENNSYLVANIA,
A CORPORATION OF WEST VIRGINIA.

GAS BURNER.

Application filed July 14, 1922. Serial No. 575,103.

To all whom it may concern:

Be it known that I, JAMES B. ANDERSON, residing in Shaler Township, in the county of Allegheny and State of Pennsylvania, a citizen of the United States, have invented or discovered certain new and useful Improvements in Gas Burners, of which improvements the following is a specification.

My invention relates to improvements in gas burners. I have developed it in application to gas burners for domestic cooking stoves, and in that application I shall describe it; but it will be understood that the invention is applicable to gas burners generally, regardless of the particular purpose for which the gas is consumed.

The particular feature of benefit and advantage of my gas burner is that I cause the minutely proportioned stream of mingled gas and air to flow in sinuous course through the burner and I form the burner orifices at the crests of the sinuosities, with this end in view; that, when the stream of fuel delivered through the burner is small, the flame shall be concentrated within a relatively small area and, proportionately as the size of the stream increases, the flame shall be spread over an increasingly larger area.

Incidentally, my burner in its construction is such as to permit its ready adaptation to varying conditions of installation, and particularly to cooking stoves of differing dimensions and proportions.

In the accompanying drawings Fig. I is a view in plan from above of a burner for a cooking stove in which my present invention is embodied. Fig. II is a view in plan from beneath of the crown plate of this burner, detached. Fig. III is a view in plan from above of the base plate, detached. Fig. IV is a view in vertical and medial section of the burner, the plane of section being indicated by the line IV—IV, Fig. I. Fig. V is a view of the burner in end elevation, but lacking the gas nozzle. Fig. VI is a view in longitudinal and vertical section of a gas nozzle with its contained valve. Associated with Fig. VI are fragmentary illustrations of the delivery orifice of the nozzle in elevation and of a certain tongue in the position it assumes as the valve is unseated. Fig. VII is a view in elevation of an adjustable disk which forms part of

the structure, detached from its associate parts. Fig. VIII is a view in side elevation illustrating the applicability of my invention in certain features to gas nozzles of different types. Fig. IX is a fragmentary view in plan from above, illustrating a modification in detail.

Referring, first, to Fig. VI, a casing 1 is provided with an inlet lead 2 and a delivery orifice 3. The valve within the casing is in its general features such as that described in my application for United States Letters Patent filed March 30, 1921, Serial No. 456,798. It may however be of different type, as for instance of the familiar rotary spigot type sufficiently illustrated in Fig. VIII.

The valve of Fig. VI (cf. Fig. IV) consists essentially of a cylindrical body 4 with conical end, mounted for axial traverse in suitable ways within chamber 1. An operating stem 5 extends through a suitable packing gland in the wall of casing 1, and in a direction at right angles to the axis of the valve body. Connection between operating stem and valve body is through a pin 6, placed eccentrically on the end of the stem 5 and entering a transverse slot 7 in the valve body. The cylindrical valve body is recessed on one side as at 8, and the enlarged end 9 of the valve stem enters the recess. The proportions are such that, as the stem is turned and the valve body shifted, the range of valve traverse is limited by abutment of the square end of the recess 8 in the valve body upon the cylindrical face of the enlarged end 9 of the operating stem. The conical end of the valve body is, as the valve is shifted, alternately seated and unseated in a properly formed orifice to control flow. The structure as thus far described is one in which accuracy and durability are combined. All of these matters are minutely described and explained in my earlier application for Letters Patent alluded to above.

The valve, as I preferably construct it, has a further and additional refinement, not shown in that prior patent application. The delivery orifice 3 of casing 1 is a contracted orifice, and the valve body terminates in a tapered tongue 10 which, when the parts are assembled and the valve seated, extends through and fills the delivery ori-

fice. As the valve recedes from its seat this tongue is to a greater and greater degree withdrawn (to the right as shown in Figure VI) and the delivery orifice is left more 5 or less completely unobstructed. The tongue is pivoted to the valve body, and when unrestrained droops from alignment in the axis of the valve body. The delivery orifice 3 is preferably square in cross section, 10 and the tongue 10 is square, tapering to an edge. The edge extends transversely to the direction in which the tongue is driven against gravity (due to its pivotal mounting) during valve closing. Accordingly, as 15 the valve recedes from its seat the tongue will uncover an increasingly widening slot, until at length the delivery orifice is completely unobstructed.

It will be understood that, tongue 10 being properly proportioned, a most minute gradation in rate of flow through delivery orifice 3 is obtained, from the cracking of the valve all the way to its position of full-est opening.

25 The gas nozzle delivers its stream axially to an induction passageway formed through the induction member 11. The gas is delivered through the end of the induction member 11, and through this end and 30 around the gas nozzle streams of air are drawn in by the rush of the gas to mingle with the gas in the passageway, and to form therein the combustible mixture. The gas nozzle is supported in the end of induction member 11 by a bridge 12.

35 Facing the bridge 12 is an adjustable ported disk 13 (cf. Figs. IV, V, and VII), and facing disk 13 is a damper disk 14. The two disks 13 and 14 are mounted for rotation on a bushing 15 carried by bridge 12 and encircling the gas nozzle. Disk 13 is manually adjustable, and provision is made, as through a segment 16 of a cylindrical shell integral with disk 13 and overlying the 40 outer surface of the induction member 11, whereby the disk when rotated to the desired position may be secured by a set screw 17. A latch 31 may be provided, for locking disk 13 against turning beyond a certain 45 point. Such latch when present may constitute a safeguard, to prevent turning by an unskilled person to a degree unsuited to the conditions of a particular installation. Disk 14 is articulated with the gas valve, 50 to the end that as the gas valve is opened and closed the damper disk 14 will rotate, and the effective area of the ports through disk 13 will correspondingly vary. Manifestly the articulation here may take any 55 suitable or convenient form. Figs. IV and VIII of the drawings show a crank pin 18 carried by the valve stem and making engagement with a crotch 19 which extends from the perimeter of the damper disk 14. 60 Fig. IX indicates that damper disk 14 may

be provided with a rack 19^a, and that this rack may be engaged by a pinion or pinion sector (I term it a "quadrant gear") 18^a borne concentrically by the stem of the valve. In either case, turning of the valve stem effects 70 a proportionate rotation of disk 14. In the specific form shown in Figs. I and IV the pin 18 is shown to be adjustable, so that it may swing on an arc of larger or smaller radius. This manifestly is a provision affording possibility of very nice adjustment 75 between valve opening and damper opening.

The valve stem, as should have been remarked above, whatever be the particular form of the valve, is provided with an operating handle 20.

The induction lead 11 at the end opposite that where the gas and air enter, is widened, and concentric circular openings of unequal diameter 21 and 22 are formed in opposite walls. These opposite walls extend in parallel planes and in normal assembly are horizontally disposed.

80 The burner is so constructed as to cause 85 the stream of gas to advance in sinuous course. At the crest of the successive sinuosities are delivery orifices for the mixture of gas and air. If the flow be small the combustible mixture will all escape 90 through the orifices in the crest of the first sinuosity, and as the flow increases the excess of flow which does not find escape through the orifices in the first crest will 95 flow on and escape through the orifices of 100 a succeeding crest or crests. Thus when the flow is small, the flame is concentrated, and as the flow increases the flame is extended over wider space.

105 Turning again to the drawings and particularly to Figures I to IV, the construction here consists essentially of three parts. The induction member 11 has already been mentioned. Assembled with it are crown piece 23 and base piece 24. The construction of the crown piece will best be understood by comparing Figure II which shows 110 it in plan from beneath with Figure IV which shows it in vertical section. It consists of an extended tubular portion 25 and 115 concentrically arranged annular folds 26, interconnected through shallow radial folds 27. At the turn of each fold a line of orifices *a* is formed through the substance of the casting of which this crown member is 120 constituted. Fig. IV shows a plurality of concentric folds, and the orifices *a* are arranged, not exactly at the crest of the turn, but at a slight interval from the crest. The orifices of the first and the second folds are 125 convergently directed, while those of the third fold are directed inwardly.

130 The base member consists of a (separable) tubular portion 30, of larger diameter than the tubular portion 25, of the crown piece,

and an essentially flat and circular plate 24 (cf. Fig. III). This base member closes the folds of member 23, and forms of each annular fold an annular chamber *b*, and of each radial fold a radial passageway. The base plate 24 carries one or more upstanding annular webs 28 and these, when the parts are assembled, entering the chambers *b*, form partitions within the chambers rising from 5 chamber floor toward the peak of the chamber, but not reaching the peak. The base plate 24 is further provided with openings *c* which, when the parts are assembled, register with spaces *d* in the casting which 10 constitutes the crown plate.

In assembly the tubular member 25 which forms part of the crown plate extends through openings 21 and 22 in the induction member. Its end is threaded to receive the 20 nut 29, and by such means the base member 24 with its tubular portion 30 is clamped between the crown member 23 and the induction member 11, and the whole is integrated and secured.

25 The flow of gas will readily be understood. Considering particularly Figure IV, the flow is longitudinal through the induction member 11 in the direction indicated by the arrow *e*. From the member 11 the flow 30 turns at right angles and enters an annular passage formed by and between the tubular portion 25 of the crown plate and tubular portion 30 of the base plate. This annular passageway is prolonged upwardly by the 35 innermost of the upstanding cylindrical webs 28. Ascending through this annular passageway the stream of gas spreads radially with respect to the axis A—B, and as it spreads it flows sinuously up and down and 40 up again. At the crests of the sinuosities the stream passes over the partition webs 28. In the trough of each sinuosity the stream passes through the connecting passageways 27. At the crest of each sinuosity some of the gas which constitutes the stream escapes. It may be that all escapes, 45 but such as does not escape goes on and ultimately reaches the crest of the next sinuosity. So long as the flow of gas is small, 50 it all will escape at the first and innermost crest; as the flow increases more and more will flow on to successive sinuosities, and so the extent of the flame will spread proportionately to the quantity of gas supplied.

55 The provisions adapting this burner for installation in stoves of different shapes and dimensions consist in forming the induction member 11 as a telescopic member, and in the clamp union between the induction member 11 on the one hand and the crown piece and base member of the burner on the other. This union admits of the introduction of a tubular portion 30 of any desired length. These features will be understood without 60 greater elaboration.

Consideration of Figure IV will show plainly the operation of this device. As the mixture of gas and air flows from orifices *a* and burns, the flame is nourished by streams of air which ascend through the central tube 25 and through the aligned openings *c* and *d* in base and crown plates. Convergence of the projected jets of flame, due to the particular correlation of orifices *a*, tends to spread the streams and to intensify 70 75 combustion.

I claim as my invention:

1. In a gas burner a burner body within which a stream of gas is caused to spread horizontally and radially from a center and as it spreads to flow in sinuous course, the burner body being provided with orifices at the crests of the sinuosities in the stream of 80 gas.

2. In a gas burner structure a plurality of concentric annular chambers connected radially at their bases and ported at their tops, the innermost chamber being incompletely partitioned interiorly by a partition web rising from the bottom of the chamber but not reaching the top, and means for introducing gas to the innermost chamber and on the inner side of the web within.

3. In a gas burner structure a plurality of concentric annular chambers connected radially at their bases and provided at their tops with convergently directed orifices, the innermost chamber being incompletely partitioned interiorly by a web rising from the bottom of the chamber but not reaching the top, and means for introducing gas to the innermost chamber on the inner side of the web within.

4. A gas burner comprising crown piece, base member, and induction member, the said crown piece being provided with a tubular extension and the induction member with opposite openings, and the base member with a separable tubular extension, and the parts being adapted to be united, the tubular extension from the crown piece extending through the openings in the induction member, and the base member with its tubular extension clamped by and between crown piece and induction member.

5. A gas burner comprising crown piece, base member, and induction member, said induction member being extensible and being provided at one end with opposite openings, said crown piece being provided with burner orifices, said crown piece and base member being provided each with a tubular extension, said crown piece and said induction member constituting when the parts are assembled clamping members between which the base member is held in place and the whole integrated, and the two tubular extensions, the one of the crown piece and the other of the base member entering when the parts are assembled the opposite open- 120 125 130

- ings of said induction member and constituting inner and outer walls of an annular passageway leading from said induction member to the burner orifices.
- 5 6. A gas burner comprising crown piece, base, and induction member, said crown piece including a central tubular member and concentrically arranged annular folds ported at the turn and interconnected by 10 radially extending shallower folds, said base including a plate adapted to engage the crown piece and close the folds thereof, and form therewith a succession of chambers with radial connecting passages, said base 15 being provided with an outstanding annulus which when the parts are assembled incompletely partitions the space within one of said chambers, and said base being further ported with openings which when the parts
- are assembled alternate with the said radial 20 passages, said induction member being provided with a gas passageway and with a transverse bore adapted to receive the tubular member of said crown piece, the outer 25 surface of said tubular member of the crown piece and the inner surface of the annulus with which said base is provided constituting, when the parts are assembled, the opposite walls of a passageway for gas, continuous with the passageway in the induction 30 member.

In testimony whereof I have hereunto set my hand.

JAMES B. ANDERSON.
